UNITED STATES PATENT OFFICE.

JOHN ROGERS, OF NEW YORK, N. Y.

DESIGN FOR A GROUP OF STATUARY.

Specification forming part of Design No. 6,548, dated April 1, 1873; application filed March 17, 1873.

To all whom it may concern:

Be it known that I, JOHN ROGERS, of New York city, have invented a Design for a Group of Statuary, of which the following is a specification:

The nature of my design is fully represented in the accompanying photographic illustration, to which reference is made.

The group consists of three figures, and is called "The Favored Scholar." The teacher is represented as leaning forward on his desk and explaining a sum on the slate he holds in his hand to a young girl standing by his side, while a boy seated on a bench behind the teacher's desk is making fun of the girl by putting curls on his ears.

What I claim as my invention is—

A design for a group of statuary, as above described.

JOHN ROGERS.
